UNITED STATES PATENT OFFICE.

JULIAN SIMON, OF ST. LOUIS, MISSOURI.

DESIGN FOR A BOTTLE.

Application filed October 15, 1928. Serial No. 28,491. Term of patent 7 years.

To all whom it may concern:

Be it known that I, JULIAN SIMON, a citizen of the United States, residing in the city of St. Louis, State of Missouri, have invented a certain new, original, and ornamental Design for a Bottle, of which the following is a specification, reference being had to the accompanying drawing, forming a part thereof, and in which—

Figure 1 is a front view,
Figure 2 is a rear view,
Figure 3 is a plan view, and
Figure 4 is a side view of a bottle embodying my new design.

I claim:

The ornamental design for a bottle substantially as shown.

JULIAN SIMON.
